W. C. REISCH,
SPRING CATCH AND LOCK.
APPLICATION FILED DEC. 21, 1920.

1,380,158.

Patented May 31, 1921.

Inventor
William C. Reisch
Seymour & Co.
Attn:

UNITED STATES PATENT OFFICE.

WILLIAM C. REISCH, OF PLANTSVILLE, CONNECTICUT.

SPRING CATCH AND LOCK.

1,380,158.

Specification of Letters Patent. Patented May 31, 1921.

Application filed December 21, 1920. Serial No. 432,228.

To all whom it may concern:

Be it known that I, WILLIAM C. REISCH, a citizen of the United States, residing at Plantsville, in the county of Hartford and State of Connecticut, have invented a new and useful Improvement in Spring Catches and Locks; and I do hereby declare the following, when taken in connection with the accompanying drawings and the characters 10 of reference marked thereon, to be a full, clear, and exact description of the same, and which said drawings constitute part of this application, and represent, in—

Figure 1, a side view of the spring catch 15 and lock, constructed in accordance with my invention, and shown in an open position.

Fig. 2, a similar view, showing the parts in a locked position.

Fig. 3, a top, or plan, view of the device, 20 with the locking plate turned to the unlocked position.

Fig. 4, a similar view, with the locking plate turned to its locked position.

This invention relates to an improvement 25 in spring catch and locks adapted for use on screen doors, trunks, automobile hoods, and in a variety of places in which a movable part is to be connected with a stationary part, the object being to provide a simple 30 construction whereby not only a spring catch is provided, but means by which the catch is converted into a positive lock, and the invention consists in the construction and arrangement of parts as hereinafter described, and particularly recited in the 35 claims.

In carrying out my invention, I form a base member 5 from a strip of sheet metal bent upward between its ends, which are 40 provided with screw holes 6, by which it may be attached, with an arch 7, and a shoulder 8. Superimposed upon the arch is a catch 9, having its rear end 10 turned downward, through a clearance-hole 11, formed 45 for it in the strap 5, and provided at its forward end with a hooked nose 12. The latch is held in place by a stud 13, formed at its lower end with a head 14, and with a shoulder 15, formed by reducing the outer end of 50 the stud. The outer end 16 of the stud is further reduced to receive a locking plate 17, which is longitudinally bowed, and formed with an operating handle 18. Upon 55 the stud below the arch is a spring 19, the strap, latch, and lock preferably formed

from strips of metal of substantially uniform width. This device is used in connection with a finger 20, provided at its end with a hook 21, adapted to pass between the nose 12 and the shoulder 8, being free to thus 60 pass between them by the yielding of the spring 19, the device thus acting as a spring catch.

To lock the finger 20, the locking plate 17 is turned into line with the catch, at which 65 time its ends bear upon the outer face of the catch and draw the shoulder 15 of the stud to a bearing against the under face of the arch, thereby any movement of the catch is prevented, so that the finger 20 can not be 70 removed. When the locking plate is turned at right angles to the catch, the catch is free to move sufficiently to release the finger 20.

I claim:

1. A spring catch and lock, comprising a 75 strip formed with an arch and a shoulder, a catch resting upon said arch and formed with a nose, a stud extending through said arch and catch, a locking plate secured to the outer end of the stud, and provided with 80 bearings adapted to be turned into the said catch, a locking finger adapted to be entered between the catch and shoulder.

2. A spring catch and lock, comprising a strip formed with an arch and a shoulder, 85 a catch resting upon said arch and formed with a nose, a spring stud extending through said arch and catch, a locking plate secured to the outer end of the spring stud, and provided with bearings adapted to be turned 90 into the said catch, a locking finger adapted to be entered between the catch and shoulder.

3. A spring catch and lock, comprising a strip formed with an arch and shoulder, a catch bearing upon said arch, and having 95 its rear end turned downward into engagement with the strip, and formed at its outer end with a nose, a shoulder spring stud extending upward through the arch and catch, a bowed locking plate secured to the upper 100 end of said stud, and a finger adapted to be entered between the catch and shoulder.

In testimony whereof, I have signed this specification in the presence of two subscribing witnesses.

WILLIAM C. REISCH.
